UNITED STATES PATENT OFFICE.

JOSEPH ANNIN, OF BROOKLYN, NEW YORK.

METALLIC WHEELBARROW.

SPECIFICATION forming part of Letters Patent No. 400,534, dated April 2, 1889.

Application filed March 5, 1886. Serial No. 194,186. (No model.)

To all whom it may concern:

Be it known that I, JOSEPH ANNIN, a citizen of the United States, residing at Brooklyn, Kings county, New York, have invented 5 certain new and useful Improvements in Metallic Wheelbarrows and Trucks, of which the following is a specification.

My invention relates to that class of barrows or trucks in which the side frame or 10 handle-bars are made of iron pipe bent at the rear ends to form the handles and curved in a downward bend at the front to receive the bearings for the wheel below the body of the barrow.

15 The invention consists in the peculiar combinations and the construction, arrangement, and adaptation of parts, all as more fully hereinafter described and claimed.

In the drawings, Figure 1 represents a side 20 elevation of my improved barrow adapted for carrying pig-iron, the dotted lines showing its position when turned up to dump the load forward. Fig. 2 is a plan view of the barrow, and Fig. 3 an enlarged cross-section thereof 25 on line *x x*. Fig. 4 is an enlarged longitudinal section of the handle end of the handle-bars. Fig. 5 is a side elevation of a hopper-barrow for coal or other loose material embodying the same improvements, except as to 30 the form of the platform. Fig. 6 is a side elevation of the wheel-supporting clip and its removable axle-box. Fig. 7 is a plan of the 35 axle-box removed. Fig. 8 is a cross-section of the clip with the axle-box shown removed below it.

Referring to Figs. 1, 2, and 3, B B indicate the handle or side bars of the barrow, which are made, as usual, of wrought-iron pipe. These bars or pipes are secured in malleable- 40 iron clasps or clips *b b c c*, which are secured on the ends of two wrought-iron cross-bars, *d e*, which underlie the tray platform or hopper A of the barrow, this part of the construction being the same in both forms of barrow shown 45 in Figs. 1 and 5, and such as claimed in my pending application, Serial No. 162,354, filed April 15, 1885.

f f are the legs of the barrow, which are made of a wrought-iron bar bent in the form 50 of a V, with one end socketed in a groove or recess in the clips *b* and bolted thereto, while the other end is bolted to the cross-bar *e* in

the manner shown in my former application. The legs are braced crosswise by an A-shaped arrangement of brace-bars, *j*, (shown in Fig. 53.) similar to what I have heretofore shown.

The tray or hopper A of the barrow (shown in Fig. 5) is made, as usual, of sheet-iron secured to the cross-bars *d e*, preferably in two pieces, the bottom being made in one piece of greater thickness, and the sides in a second piece of less thickness, bent into form and riveted to the bottom piece, as shown in my former patent, No. 305,879, dated September 30, 1884. In my leading form of barrow, (shown in Fig. 1,) however, the tray A, instead of being made of a continuous sheet of iron is made up of a series of thin parallel wrought-iron bars, *h h*, set up edgewise on the cross-bars *d e*, and secured thereto at three points by the angle-irons or brackets *g g*, as seen best in Fig. 3, the bars *h h* being secured firmly together by the stay-bolts *i i* at four points, as seen in Figs. 1 and 3. The stay-bolts *i* pass transversely through the entire series of bars, as seen in Fig. 3, which are held on the said bolts at the proper distance apart by intervening collars or washers *k k*, as seen in Figs. 2 and 3. The tray-bars *h h* are not straight throughout, but are bent at or near the middle in a 80 V form, so that the rear part of the tray is level, while the front part inclines diagonally forward over the wheel, as shown in Fig. 1. I prefer to combine a series of different forms of wrought-iron bars in the said tray, as 85 shown best in Fig. 3, the center bar being a T-bar, the two outer bars being angle-bars, while the bars between are partly channel-irons and partly plain flat bars, and are all so placed as to form a level top to the tray, 90 the level or horizontal part of the angle T and channel-bars being on a line, as shown in Fig. 3. It may now be seen that this form of tray is not only very light, but exceedingly strong, as it is composed of a series of iron bars set up 95 edgewise in the position of greatest strength and greatest range of wear, and is thus admirably adapted for the carriage of pig-iron and similar heavy weights, as it is not likely to be bent or dented by the shock of the pigs in 100 loading or unloading, and is thus very substantial and durable.

It will be seen that by having angle-bars at the extreme edges of the tray, as seen in Fig.

3, additional strength is secured at the edges where most required, and the edge bars are thus made to overhang and project beyond all other parts of the underlying frame, which 15 is an advantage, as it insures more easy loading and unloading and protects the under frame from contact with the pigs.

Referring now to Fig. 1, it will be seen that the frame-tubes B are cranked or bent up at 10 the rear ends to form the handles of the barrow, and are also bent in a downward double-cranked bend at the front, at the point a, to receive the bearings for the wheel m. The slightly-curved middle of the bends a are embraced by the bisected clips l l, as seen in Figs. 1 and 5, and enlarged in Figs. 6 and 8, and are firmly held in place by the bolts n, the said clips carrying the axle-boxes o, in which the axle of the wheel is journaled.

20 In my former barrows the axle-box was integral with the clips; but in my present improvement it is made separate, as seen best at o in Figs. 7 and 8, the clips l l having a rectangular recess, q, at the base to receive 25 said boxes. (Seen by dotted lines in Fig. 6 and full lines in Fig. 8.) The box o is a substantially rectangular block of malleable iron having a round bore to receive the journal end of the axle and a square exterior to 30 fit the recess q, with flanges p extending beyond the square to overlap the socket in the clip, as seen in Figs. 6 and 7, the flanges being secured to the clips by the pins or rivets r. By this means it will be seen that the 35 wearable part of the wheel-bearings or axle-box proper is made removable, and when worn out can be easily displaced by removing the pins r and replaced by a new box at small cost without having to remove the entire clip, as was the case with the former construction.

Now, referring again to Figs. 1 and 5, it may be seen that the bend a in the pipe A, to receive the wheel-bearings, is made much 45 lower than usual and much nearer to the center of the barrow than usual, and it is so proportioned and disposed as to bring the center of the wheel far below the center of gravity vertically and close to it horizontally, so that a line drawn through the center of gravity will make an acute angle with a vertical line through the center of the wheel, as shown by the dotted lines x and y in Figs. 1 and 5. The point x indicates the 55 center of gravity of the barrow, and it will be seen that the arc between that and the vertical center line is not much over forty-five degrees, or usually about fifty degrees; hence it will be only necessary to raise the 60 barrow through that small arc to make it balance on the axle, as indicated by the first dotted position in Fig. 1, at which position the load will commence to dump forward, and by continuing to tilt the barrow a little farther 65 forward the whole load may be easily dumped straight forward over the wheel and depos-

ited on the ground or floor in front of the barrow. It will therefore be seen that by reason of this position of the center of gravity relatively to the axle, and the small arc 70 of motion necessary for dumping forward, this dumping motion is within the convenient and easy scope or reach of a man's arms reaching forward, as indicated in Fig. 1, and that, furthermore, the direct forward 75 thrust of both arms may be used in this dumping movement, which is, in fact, the strongest, easiest, and most natural movement of the human arms in exertion. On the contrary, when the barrow is dumped sidewise almost 80 all the strain is exerted by one arm on one handle of the barrow, and with a sidewise twist, which is not easy or natural. It will be further seen that not only does this construction enable the barrow to be dumped by 85 the easy forward reach of the arms, but besides this the leverage at the handles over the load is greatly in favor of the workman and is at a ratio of about six to one, as may be readily seen by referring to Figs. 1 and 5. 90 Hence this barrow, when loaded, is very easily handled on account of the small proportionate weight borne at the handles, and as it is tipped up to dump the load the strain at the handles becomes less and less until it is practically nothing at the position of balance, when the workman has the load under perfect control, and by a slight additional forward movement may then dump it straight forward in front of the wheel, which will generally deposit the load much nearer the desired locality than can be done by dumping 100 sidewise.

Previous to my invention all barrows of this class were adapted to dump sidewise 105 only, which strains the barrow greatly, requires much more exertion and is much less convenient, and moreover the workman has to exert the greatest strain and care at the moment of dumping, whereas in my improved 110 barrow the barrow is balanced just before the moment of dumping, and the strain is also equalized thereon and requires but slight exertion to effect the dumping, thus rendering the barrow at all times under perfect and 115 easy control of the workman, which are great advantages.

Now, in order to prevent the barrow tipping over too far or recoiling when the load is dumped, I form the forward end of the pipes 120 B with an additional bend, s, as seen in Figs. 1 and 5, which bends are directed out beyond the wheel and diagonally downward, the terminal end of the pipes beyond said bend being finally riveted to the tray of the barrow, 125 as usual. These bends s s form knees or rests, which will strike the ground in advance of the wheel and thus support the barrow in the overturned or dumped position, as indicated by dotted lines in Figs. 1 and 5, and 130 thus prevent any recoil of the wheel or of the body of the barrow backward against the

workman's feet or body, which is a very desirable feature in the practical working of the barrow.

It is well known that when metal-handled trucks or barrows are used out-of-doors in very cold weather that the metal handles cannot be seized in the naked hands without danger of the hands sticking or freezing thereto, so that gloves or protectors have to be used on the hands, which is often objectionable. To obviate this objection I provide the handle ends of the metal tubes A with a non-conducting sheath, *t t*, made of a tube of prepared or toughened paper of the nature of parchmentized, vulcanized, or gelatinized fiber paper, this paper tube being slipped tightly over the ends of the metal tube, as shown in Fig. 4. I prefer, as well shown in Fig. 4, to reduce the handle end of the tubes B by rolling the same down to a reduced diameter, and I then force the paper tubes *t* on the reduced parts, making them of sufficient thickness to come about flush with the unreduced part of the tubes, as illustrated, thereby producing a neat appearance and affixing the non-conducting handle securely to the metal tubes without increasing the size of the handle from the usual. A paper handle of the described kind possesses great advantages in lightness, toughness, durability, and non-conductivity, and greatly adds to the value of the barrow, for not only does it make the grasp on the barrow more pleasant and secure, but enables the barrow to be handled in the coldest weather without any difficulty, which is a great advantage over the metal handles heretofore used. Not only is this non-conducting handle of great value in cold weather, but it is equally so in hot weather, particularly in hot countries, in which it has been impossible heretofore to use metal barrows without protection for the hands, as the metal gets sufficiently heated when exposed to the sun as to be insupportable to the naked hands. By means of my improved paper handle not only can the barrow be handled easily in the coldest or hottest weather or climate, but the material affords greater frictional adhesion for the hand than is the case with iron, and is particularly tough and durable.

I am aware that rawhide has been used to cover the iron handles of barrows; but this is affected by the weather, being softened and weakened by wet and shrunken by heat and dryness, whereas the toughened or parchmentized paper is proof to all weathers and all atmospheric temperatures, is a better non-conductor, has greater strength, is more durable, and is cheaper, and thus forms an improved handle.

Several of my improvements herein described apply of course equally well to wheeled trucks as to barrows, and as concerns several features of my invention I consider a truck the equivalent of a barrow.

What I claim is—

1. A wheelbarrow having its tray or platform made of a series of parallel iron bars set up edgewise and secured together, substantially as set forth. 70

2. A wheelbarrow having its tray or platform made of a series of iron bars, *h h*, set up edgewise and secured together in parallel lines, but bent at or about the middle, so that 75 one half of the bars extends inclined to the other half, substantially as set forth.

3. A wheelbarrow having its tray or platform made of a series of parallel iron bars set up edgewise and secured together, the outer 80 or marginal bars being angle-irons arranged substantially as shown and described.

4. A wheelbarrow having its tray or platform made of a series of parallel iron bars set up edgewise and secured together, the middle 85 bar being a T-iron and the outer marginal bars angle-irons, arranged substantially as shown and described.

5. In a wheelbarrow, the combination, with the side bars or tubes, B, and cross-bars *d e*, 90 secured thereto, of the tray-bars *h*, set up edgewise thereon in parallel files and secured thereto, substantially as shown and described.

6. The combination of the side bars, B B, clips *b c*, cross-bars *d e*, and tray-bars *h h*, 95 secured together, substantially as shown and described.

7. In a wheelbarrow or its equivalent, the combination, with axle clips or bearings formed with a recess or socket, of the removable 100 axle-boxes *o o*, arranged to fit into said sockets, and a fastening to hold the same in place and permit the removal and renewal of said boxes, substantially as herein set forth.

8. In a wheelbarrow or its equivalent, the 105 combination with the side bars or tubes, B B, and bisected clips *l l*, embracing said bars to support the wheel-axle with the removable axle-boxes *o*, arranged to engage with said clips, substantially as and for the purpose set 110 forth.

9. In a truck or barrow, the combination, with the side bars, B, of the bearing-clips *l*, arranged to be clasped thereon and formed with a recess or socket, *q*, of the removable 115 axle-boxes *o o*, having a waist to fit said socket and overlapping flanges *p p* to embrace the clip, and a fastening to secure the box in place and permit of its removal and renewal, substantially as shown and described. 120

10. In a truck or barrow, the combination, with metallic handle bars, of paper tubes incasing the bars at the handle ends and tightly secured thereto and forming the grasping portion of the handles, substantially as and 125 for the purpose set forth.

11. In a truck or barrow, metallic handle-bars rolled down or reduced in diameter at the handle or grasping end, in combination with a tube or sheath of non-conducting material incasing the reduced end and secured thereto flush, or nearly so, with the remainder of the bar, substantially as shown and described. 130

12. In a truck or barrow, the combination, with the metallic tubular side bars, B B, rolled or reduced in diameter at the handle ends, of the paper tubes t , secured on said reduced parts and forming non-conducting handles thereon, substantially as shown and described.

13. In combination with the metallic side or handle bars of a truck or barrow, sections of toughened paper, of the nature of parch-

10
mentized, vulcanized, or gelatinized fiber, secured to the ends of the metallic tubes and forming non-conducting, tough, and durable grasping-handles thereon, substantially as set forth.

JOSEPH ANNIN.
